BED DAVENPORT

Horner W. Young, Springfield, Mo.

Application January 30, 1942, Serial No. 428,882

6 Claims. (Cl. 5—37)

This invention relates to improvements in bed-davports and particularly to a bed-davenport in which a pair of articulated sections are extendible to form a bed and convertible in a manner whereby one of the sections is utilized as a back-rest while the other forms a spring base for removable loose cushions which are disposed on the base to form a seat.

In bed-davenport construction a general practice has developed in which a spring equipped and padded vertically disposed back rest section is articulated with a similar horizontally disposed seat section with the axis of the hinge means disposed substantially at the line of juxtaposition of the padded sections and lying substantially in the top plane of the spring assemblages. Various locking devices are utilized for securing the sections in right angled co-relation while in seating position and while being rotated to a position in which the back rest portion assumes a horizontal position, the locking means being adapted to be disconnected to allow the seat section to be lowered to a bed position co-planar with the rear section. The general practice is to construct the sections as separate units, individually sprung and upholstered, and having a hinge at each end for articulation and for holding the sections in operable co-relation. A supporting frame work is usually provided in which a box-like part is employed as a base, the ends of which provide supporting means upon which the seat section rests when the device is used as a seat and upon which both back and seat sections rest when used as a bed.

In such structures, as well as in various other structures of the prior art, it will be observed that the sections when converted into a bed are disposed at the same height as the seat of the unconverted device, which is considerably lower than standard bed height. It is also noted that in such structures the front to back width of the sections when extended to bed-position is the same as the combined seat and back-rest dimensions, which according to conventional standards are approximately 22 inches and 22 inches respectively or 44 inches in combination, which is considerably less than standard bed width.

In such structures, due to the non-continuous structure of the sections, a crank or opening is in evidence at the juncture of the sections which necessitates the use of a separate pad when used as a bed to protect the user against drafts of air through such openings. Also in such conventional devices the seat portion is crowned or oval instead of flat. This structure lends to the ap-

pearance and comfort of the device as a seat but when converted into a bed the oval structure presents an uncomfortable ridge or hump and an accompanying depression between the sections.

5 One of the principal objects of my invention is to provide a convertible bed-davenport having a pair of spring-equipped and padded articulated sections which when extended to form a bed will have a greater front to back dimension than the combined back-rest and seat dimensions of the device.

Another object is to provide a device of this character in which the padding of the bed sections comprise a continuous unbroken, unitary structure which will provide a smooth, level bed surface when extended to form a bed.

A further object is to provide a bed-davenport in which a spring base is provided for supporting removable spring-filled cushions and in which the spring base is compressible at the front to provide a so-called soft front.

20 Another object of my invention is to provide a means whereby the sections, when extended to form a bed, are disposed at a higher level than the seat of the device when closed.

25 Another object is to provide a device of this character having a pair of spring equipped articulated bed sections and a continuous unitary padding structure as previously noted and in which a double parallel hinge means is provided at the juncture of the spring assemblages of the bed sections whereby excessively acute bending or folding of the padding at this juncture is eliminated.

30 Another object is to provide an articulating means for the bed sections in which the longitudinal axis of the hinges interconnecting the frames of the bed sections is positioned below the articulating means interconnecting the top portions of the spring assemblages when the sections are in the extended position and in which means is provided for depressing the spring assemblages at their articulated juncture as the bed sections are folded and whereby the articulating means for the spring assemblages will be shifted with relation to the axis of the bed frames hinge means.

35 Another object is to provide a bed davenport with articulated bed sections, one of which serves as a back rest when used as a seating device and in which the rear extremity of the back rest will follow a vertical straight-line path in traversing from a seating position to a bed position whereby the device may remain disposed against a wall 40 while being operated.

Another object is to provide a means for depressing the rear of the spring assemblage which forms the spring base for loose seat cushions when the device is folded into seating position, whereby to prevent a rigid holding of this portion of the spring base at a non-depressed level and whereby proper depression of adjacent forwardly disposed portions is facilitated and a forwardly sloping condition is prevented when the seat is occupied.

A further object is to provide a bed davenport in which the portion comprising the sleeping equipment or bed is not utilized directly as a seat cushion and is not subjected to the severe usage received by a seat cushion.

Further objects of this device reside in any novel features of construction or operation or novel combination of parts present in the embodiment described and shown in the accompanying drawings, whether within or without the scope of the appended claims and irrespective of other specific statements as to the scope of the invention contained herein.

In accomplishment of these objects I have provided a supporting frame, a vertically disposed, coil spring equipped back rest section which extends below the seat cushions which are separate units. Articulated with the back rest section is a horizontal section similarly equipped with a coil spring assemblage and which is disposed near the bottom of the frame and serves as a spring base for supporting the separate removable cushions.

The sections are provided with interlocking means for securing them in right angled co-relation and the rear or back-rest section is provided with trunnions at each end which provide a longitudinal axis upon which the interlocked sections may be rotated. This axis is located in spaced relation with the axis of the articulating means which interconnects the sections and so located upon the rear section that when it is rotated to a horizontal position it will be disposed at a higher level than the seating height of the closed device.

The frame of the device has end members which support the trunnions of the back rest and the latter are provided with means whereby they may be shifted forwardly as the rear section is rotated from a back rest position to a horizontal position.

Interconnecting means associated with the end members provide a means for shifting the trunnions forwardly and backwardly as the rear section is rotated respectively to and from a horizontal position.

The interlocking means for holding the sections in right-angled relation are adapted to also form supports for the front section when the latter is lowered to a bed position co-planar with the horizontally disposed back rest section, the supports being adapted to rest on a portion of the frame.

The sections of my device have separate frames which carry the articulating means for interconnecting the sections and carry separate coil spring assemblages which support a continuous unitary pad of uniform thickness which forms the surface of the bed. The spring assemblages are interconnected at their juncture by dual parallel hinge means at the tops thereof which permits the spring assemblages and the padding thereon to fold along two parallel lines when the sections are folded to right angled relation. Means is provided for depressing the springs along their

hinged juncture as the sections are folded. The axis of the hinge means interconnecting the front and back sections is disposed below the hinged juncture of the spring assemblages when in the horizontal extended position. By virtue of this axial spacing of the articulating means the spring assemblages are forced toward each other at their top edges as the sections are folded to right angles. As this occurs the aforementioned depressing means draws the articulated portion of the spring assemblages toward the axis of the section hinge means to take up the slack occurring at the top of the springs and in the padding thereby keeping the padding tight and at the same time depressing the padding at this point so that when the front section is disposed in a horizontal position near the bottom of the frame the rear portion of this section will be pre-depressed. Such pre-depression along the rear of this section permits the proper depression of forwardly disposed portions thereof when used as a spring base for supporting separate loose cushions. With this structure the rear of the front section is not held rigidly at an undepressed level which would result in a forwardly sloping structure when depressed in other regions.

In further detail and with reference to the accompanying drawings,

Fig. 1 is a perspective view of my device as a seat.

Fig. 2 is a perspective view showing the device with the cushions removed and the sections rotated to bring the back-rest to a horizontal bed-position.

Fig. 3 shows the device with the front or spring-base section lowered to a bed-position.

Fig. 4 is an end view of the device as a seat, with portions of the frame cut away to show mechanism.

Fig. 5 is a similar view showing the sections rotated to bring the back rest to bed-level.

Fig. 6 is a similar view showing the front section lowered to a bed-level.

Fig. 7 is a fragmentary sectional view taken on 7-7, Fig. 5. Fig. 7A is a fragmentary horizontal sectional view taken on 7A-7A, Fig. 7, showing the parts in disassembled relation.

Fig. 8 is a fragmentary view showing portions of the spring assemblages and their interconnecting and depressing means.

Fig. 9 is a sectional view taken on 9-9, Fig. 8, showing the spring assemblage interconnecting and depressing means in the extended or bed position.

Fig. 10 is a similar view showing the position of the parts when the sections are in seating position.

Fig. 11 is a perspective view of the interconnecting hinge means for the spring assemblages.

Fig. 12 is a vertical section showing the interconnecting hinge means with the padding attached thereto by cords at the hinge points.

Throughout the various views the same characters represent similar parts.

1 represents the spring equipped and padded rear or back-rest section which is articulated with the similar front or spring base section 2 by offset hinges 3 at each end. A frame or case is provided in which a front rail 4, a rear panel 5 and a bottom board 6 interconnect end members 7 to form a box to the end members of which are secured arm members 8 which may be of any desired style and attached to the end members of the box by bolts, screws or otherwise.

Trunnions are secured to the back rest sec-

tion at the rear thereof and in spaced relation to the hinge 3 to form an axis upon which the sections may be rotated. In the present embodiment the trunnion means comprises a shaft 9 held by the bracket 10 (the shaft may be held against endwise movement by cotter keys). The brackets are secured to the frame 11 of the rear section 1 by screws or other suitable means. The shafts 9 extend outwardly of the section 1 and carry at their outer ends rollers 12 which engage oblong tracks 13 supported in suitable slots in the end members 7, the tracks being held in place by nails or screws. The rollers 12 are flanged to limit their entrance within the tracks.

The rear section is adapted to be disconnected from the box by withdrawing the shafts 9 from the rollers 12.

Locking means for holding the sections in folded relation comprise toggle links 14 and 15 pivotally attached respectively to sections 1 and 2 at 14A and 15A and which assume an extended or over center position when the sections are folded to the position indicated in Figs. 1, 2, 4 and 5. Springs 16 hold the toggle links in their extended position with the inwardly turned portions 17 of the toggle links 15 resting against the frame of the front section.

The toggle links also serve as supports for the front section when the latter is extended as a bed as in Figs. 3 and 6, in which position the toggle links are folded to a substantially right angled co-relation. The inwardly turned portions 17 rest on the front rail 4 when the front section 2 is extended as a bed. The springs 16 are adapted to assist in raising the front section from a bed position by urging the toggle links toward their extended position.

Links 18 pivoted to the end members of the box at 19 and to the rear or back rest section 1 at 20 serve to support this section in back-rest position as in Fig. 4 and to force the trunnions forwardly on the tracks 13 when the section is rotated to a horizontal position as in Fig. 5. Springs 21 attached to the links 18 and having their lower ends attached to the end members of the box as indicated at 22 serve to counterbalance the folded sections and aid in rotating these members.

Referring particularly to Figures 8 to 12 inclusive, 11 and 23 represent the frame work respectively of sections 1 and 2 to which are attached suitable cross supports for the spring assemblies. 24 and 25 indicate respectively the coil spring assemblies of the rear and front sections. These are of the conventional type comprising compression coils interconnected at their tops by spiral spring ties. Wire links 26 attached to the front and rear spring assemblies by spiral clips 27 form a double parallel hinge articulating means between the front and rear spring assemblies. The clips 27 disposed on the end portions of the links 26 as in Fig. 11 are adapted to secure the links to the coils by engaging the ends of the clips 27 over adjacent coil loops and rotating the clip until its opposed spirals draw the links into the position shown in Fig. 8 when the ends are hooked under the top loop of the coil.

The pendant portions of the links 26A are adapted to engage loops of cord 28 which have one of their ends secured to the frame of the front section by the eyes 29 while the opposite ends are secured to the frame of the rear section by the hooks 30.

A unitary pad 31 of uniform thickness is dis-

posed continuously over both front and rear spring assemblies and is attached to the spring units at each interconnecting hinge loop by tufting cords 32. 32 is a padded roll at the front edge of the front section 2 which is adapted to aid in retaining the removable loose cushions 34 which form the seat of the device. The cushions are of the conventional spring-filled type.

10 A tube or rod 35 rigidly interconnects the links 15 of the toggles to hold them in parallelism and to serve as a handle by which the toggle links may be pulled forwardly to release the sections from their interlocked right-angled position and allow the front section to descend to a horizontal position.

15 It is noted that by detaching the bracket 36 which carries the pivot means 15A and detaching the cords 28 from the hooks 30 the front section 2 may be folded over on top of the rear section 1 in face to face relation. It is further noted that by detaching the links 18 from the end members of the box at 19 and detaching the rollers as previously described the folded (face to face) sections may be deposited within the box for storage or shipping.

20 In operation the device is changed from a seat (Figs. 1 and 4) to a bed by removing the loose cushions 34 and raising the front edge of the spring base section 2 to rotate the interlocked sections rearwardly until the rear section 1 rests upon the rear panel board 5 (Figs. 2 and 5); then the front section 2 is lowered (after releasing the toggles by pulling forward on the tube 35) to a position coplanar with the rear section 1, whereupon the toggles will contact the front rail 4 to form a support for the front section (Figs. 3 and 6).

25 To convert from a bed to a seat the front section 2 is raised to the position shown in Figs. 2 and 5 whereupon the springs 16 will force the toggles into their extended or dead center position to interlock the section in this folded relation. The interlocked sections are then rotated by pulling downward on the front section to bring the sections to the seating position with the front section resting upon the front rail 4. The cushions are then replaced to form a seat (Figs. 1 and 4).

30 It will be noted that in the present invention the axis or pivot means on which the sections rotate (when locked in a right angled relation) is separated from the axis of the hinge means interconnecting the front and back sections and that the former is so located and spaced from the latter that when the sections are rotated to the seating position, the front section is lowered to a position near the bottom of the box instead of at the conventional seat level.

35 It is also noted that with the above structure the back rest member is of considerably greater top to bottom dimension than the conventional type structure and that this extra width is utilized in a manner that results in a greater front to back width of the bed when the sections are extended.

40 With the present structure the back rest is carried forward at its axis when rotated from a back rest position to a horizontal position by the links 18 in such a manner that the rear extremity of the back rest follows a straight-line vertical path thereby permitting the device to remain disposed against a wall while being operated; and due to the location of the axis upon the back rest the sections are elevated to a greater height when in

bed position than the seat height of the closed device.

It will be noted that provision is made for a continuous pad of uniform thickness which is extendable into a flat, even bed surface and which when folded is depressed at the juncture of the sections in a manner that prevents strain upon the pad when the front section is depressed by the user and which allows the free depression of the spring base forwardly of the juncture which assures a comfortable seat.

While the flat, even surface is provided for the bed sections, a suitable oval or crowned seat structure is obtained through the use of separate loose cushions in combination with the front bed section as a spring base for the cushions. This combination has the additional advantage of a deep spring seat comprising a spring filled cushion and a soft front spring base for a cushion support. Through this arrangement the front bed section is not subjected to the hard usage received by similar sections of conventional devices inasmuch as the cushions are utilized as direct seating equipment instead of the bed section.

I claim:

1. A bed davenport comprising a supporting frame having end members; a pair of bed sections disposed longitudinally between said end members and forming front and rear bed sections; articulating means interconnecting said sections and adapting them to be extended to a co-planar horizontal position to form a bed and to be folded in substantially right angled co-relation; locking means for holding said sections in said right-angled co-relation; trunnions carried by the rear bed section, said trunnions being disposed at each end of said rear section and in transversely spaced relation with the articulated juncture of said bed sections; means carried by said end members for supporting said trunnions whereby the trunnions may be shifted forwardly and backwardly on said end members; said folded and interlocked sections being adapted to be rotated on said trunnions to a position wherein the rear section occupies a back rest position and the front section occupies a substantially horizontal position near the bottom of said frame to provide a base for supporting removable cushions and means for shifting the trunnions on the end members when the bed sections are rotated, said means comprising at each end of the rear section a link having one of its ends pivotally supported at the rear of the end member and having its other end pivotally connected with the rear section at a point midway between the trunnion and the rear extremity of the rear section whereby the rear edge of the back rest section will be disposed substantially flush with the rear of said end member when in a horizontal position.

2. A bed davenport comprising a supporting case having end members; a pair of bed frames; articulating means interconnecting said frames; coil spring assemblages carried by said frames; hinge means for interconnecting the spring assemblages at the tops thereof; said frames and spring assemblages comprising front and rear bed sections adapted to be extended to a coplanar horizontally disposed position to form a bed; the axis of said bed frame articulating means being disposed above said frames by a distance in excess of one-half the depth of said spring assemblages and below the tops of said spring assemblages when the sections are in an extended hori-

zontal position; said spring assembly, hinge means and said bed frame articulating means adapting said sections to be folded in a substantially right angled co-relation, locking means for holding said sections in said folded position; laterally extending pivot means carried by the lower end of the rear section and being movably supported by said end members whereupon said folded sections are adapted to be rotated to a position in which the rear bed section occupies a substantially vertical back rest position while the front bed section occupies a substantially horizontal position near the bottom of said case to form a base for supporting removable seat cushions; links interconnecting the rear bed section and said end members for shifting said sections forwardly and backwardly upon said pivot means while being rotated and means for depressing the spring assemblages adjacent their interconnecting hinge means as the sections are folded to right angled co-relation, said depressing means comprising a series of longitudinally spaced flexible members, each having one of its ends attached to the rear bed frame and its other end attached to the front bed frame, the length of said members being such that they will be substantially tight when the bed sections are in a right angled position, and means interconnecting the mid-portions of said members with the hinge means interconnecting the tops of said spring assemblages, the length of the interconnecting means being such that the spring assemblages will be depressed thereby as the flexible members are tightened.

3. A bed davenport comprising a supporting frame having end members, a pair of bed sections disposed longitudinally between said end members and forming front and rear bed sections; articulating means interconnecting said bed sections and adapting said sections to be extended from a co-planar horizontal position to a substantially right angled co-relation; means releasably connecting said sections for locking the latter in said right angled co-relation; laterally extending pivot means carried by the lower end of the rear bed section and being axially spaced from said articulating means; means for supporting said pivot means upon the end members of said frame for movement forwardly and rearwardly thereupon whereby said bed sections, when in interlocked right angled relation, may be rotated upon said pivot means from a seating position with the rear section forming a substantially vertically disposed back rest and the front section substantially horizontally disposed to a position with the back rest section substantially horizontally disposed, means for carrying said pivot means forwardly and backwardly comprising a link member at each end of the back-rest section for interconnecting the latter with said end members, each of said link members having one end thereof hinged to one end of the back rest section substantially midway between said longitudinal pivot means and the outer extremity of said back rest section and having its other end hinged to the end member of said frame near the rear thereof and substantially at the same height as the longitudinal pivot means whereby when the sections are rotated from a seating position to a position with the back rest section horizontally disposed the top of the back rest section will move in a substantially vertical plane.

4. A bed davenport comprising co-articulated seat and back-rest frames adapted to be extended to a co-planar horizontal position to form a bed;

spring assemblages carried by said frames; hinge means interconnecting the tops of said spring assemblages; and means for depressing said spring assemblages at their hinged juncture as said frames are folded from a co-planar position to an angular co-relation, the co-articulating means of said frames having its axis disposed at a distance above the frames in excess of one-half the depth of said spring assemblages and below the tops of said spring assemblages; said depressing means comprising a plurality of flexible means associated with said frames and said spring assemblages and being longitudinally spaced, each of said means comprising a flexible element having one end thereof attached to the seat frame and its other end attached to the back-rest frame, and a second element having one end thereof attached to the hinged juncture of the spring assemblages and its other end attached to said flexible element adjacent the middle thereof, said second element being of such length that its juncture with said flexible element is positioned below the axis of said co-articulating means interconnecting the seat frame and the back-rest frame; said flexible element being of such length that the interconnected element will be drawn to a substantially fully extended condition when the frames are in a co-planar relation and with the flexible element substantially folded upon itself; said flexible element being adapted to be drawn from a substantially folded position toward an extended straightened position as said frames are folded to an angular co-relation, whereby the said second element will depress the spring assemblages adjacent their articulated tops.

5. A bed davenport comprising a supporting frame having end members; a pair of bed sections disposed longitudinally between said end members and forming front and rear bed sections; articulating means interconnecting said bed sections and adapting said sections to be extended from a substantially right angled co-relation to a coplanar horizontal position; means releasably connecting said sections for locking the latter in said right angled co-relation; laterally extending pivot means carried by the rear bed section, the axis of said pivot means being adjacent the rear of said section and in spaced relation to the lower extremity thereof; means for supporting said pivot means upon the end members of said frame for movement forwardly and rearwardly thereupon whereby said bed sections, when in interlocked right angled relation,

may be rotated upon said pivot means from a seating position with the rear section forming a substantially vertically disposed back rest and the front section substantially horizontally disposed to a position with the back rest substantially horizontally disposed; means for carrying said pivot means forwardly and backwardly during said rotation comprising a link member at each end of the back-rest section for interconnecting the latter with said end members, each of said link members having one end thereof hinged to one end of the back-rest section between said longitudinal pivot means and the outer extremity of said back-rest section and having its other end hinged to the end member of said frame near the rear thereof whereby when the sections are rotated from a seating position to a position with the back-rest section horizontally disposed the longitudinal pivot means will be moved forwardly on the end members of the frame by the link members.

6. In a bed davenport having seat and back-rest sections adapted to be folded to substantially right angled co-relation and to be extended to a co-planar horizontal co-relation, frames for each of said sections, each of said sections having a longitudinal member at its inner edge, said longitudinal members being in juxtaposed relation when said sections are in coplanar relation; spring units carried by said frames; longitudinal hinge means interconnecting said spring units adjacent the tops thereof; longitudinal articulating means interconnecting said frames, the axis of which is disposed below the axis of said spring hinge means and spaced above said frames by a distance in excess of one half the depth of said spring units whereby when said sections are folded to a right angled co-relation said longitudinal members will be disposed in spaced relation; longitudinally spaced pendant links carried by said spring units adjacent their hinge means, the lower portion of said links being disposed below the axis of said frame articulating means when said frames are in co-planar co-relation; a flexible member carried by the lower portion of each of said pendant links, one end of said flexible member being attached to the longitudinal member of the seat section frame and the other end of said flexible member being attached to the longitudinal member of the back-rest section frame, whereby when the sections are folded to right angled relation the flexible member will be extended toward a lineal relation.

HOMER W. YOUNG.
